UNITED STATES PATENT OFFICE.

JOHN P. RITCHIEY, OF FINDLAY, OHIO.

SPARK PLUG.

Application filed November 12, 1921. Serial No. 514,682.

To all whom it may concern:

Be it known that I, JOHN P. RITCHIEY, citizen of the United States, residing at Findlay, in the county of Hancock and 5 State of Ohio, have invented certain new and useful Improvements in Spark Plugs, of which the following is a specification.

This invention relates to an improved spark plug and seeks as one of its principal 10 objects to provide a plug embodying a plurality of spark gaps for increasing the efficiency of the plug.

A further object of the invention is to provide a plug wherein flow of current through 15 the main electrode of the plug will be interrupted by a plurality of gaps arranged near the upper end of the plug and wherein said gaps will be enclosed and protected.

And the invention has a still further object 20 to provide a plug wherein flow of current from the main electrode of the plug to the shell will be interrupted by a plurality of spark gaps across which the current must jump to reach the shell for thus insuring 25 dependable firing of the plug.

Other and incidental objects will appear hereinafter.

In the drawing:

Figure 1 is a vertical sectional view taken 30 medially through my improved plug, and

Figure 2 is a bottom plan view of the plug.

Referring now more particularly to the drawing, I employ a shell 10 threaded at its lower end for engagement in the usual spark plug orifice of an engine cylinder and fitting through the shell is an insulator 11. This insulator may be of porcelain or other approved material and formed thereon is an 35 annular shoulder 12 beneath which is arranged a gasket 13 and overlying said shoulder is a similar gasket 14. Threaded into the shell to coact with the latter gasket is a nut 15 firmly binding the insulator upon the shell, the gaskets serving, of course, to provide sealed joins between the insulator and the shell. At its lower end the insulator 40 preferably projects below the lower end of the shell and embedded in the insulator is a main electrode 16. At its lower end this electrode projects below the insulator while at its upper end said electrode is provided with a laterally directed terminal 17 entering a spark cup or recess 18 in one side of the insulator. Extending diametrically of 45 the insulator is a transverse electrode 19 one end of which projects into a spark cup

20 in the side of the insulator opposite the cup 18 while the other end of said electrode is formed with a depending terminal 21 entering the cup 18 to provide a spark gap 60 between said terminal and the terminal 17 of the electrode 16. Extending diametrically through the insulator above the electrode 19, in spaced parallel relation thereto, is a transverse electrode 22 one end of which 65 enters a spark cup 23 in the insulator above the cup 18 while the opposite end of said electrode is provided with a depending terminal 24 entering the cup 20 to provide a spark gap between said terminal and the 70 adjacent end of the electrode 19. Extending diametrically through the insulator above the electrode 22 in spaced parallel relation thereto, is a transverse electrode 25 one end of which enters a spark cup 26 in 75 the insulator above the cup 20 while the opposite end of said electrode is provided with a depending terminal 27 entering the cup 23 to provide a spark gap between said terminal 80 and the adjacent end of the electrode 22. 85

As will thus be seen, the electrodes 19, 22 and 25 are all similar in construction and formed on said electrodes or otherwise secured thereto are bosses 28 securing said electrode against endwise movement. The main electrode 16 85 is also preferably provided with a similar boss 29. Embedded in the upper end portion of the insulator is an electrode 30 projecting through the upper end of the insulator and offset to define a terminal 31 entering the spark cup 26 to provide a spark gap 90 between said terminal and the adjacent end of the electrode 25. Snugly but removably fitting over the upper end portion of the electrode is a frusto-conical protecting jacket 95 32 and arranged between the lower end of said jacket and the nut 15 is a preferably asbestos gasket 33. At its upper end the jacket terminates flush with the upper end of the insulator and fitting over the projecting end of the electrode 32 to overlie said jacket is a washer 34. Threaded upon the electrode to coact with this washer is a nut 35 and coacting with said nut is a binding nut 36 for connecting a circuit wire with the electrode. Embedded in the lower end of the insulator is an electrode 37 cooperating with the electrode 16 to provide a spark gap therebetween. The insulator also carries a somewhat longer electrode 38 cooperating with 100 the electrode 37 to provide a spark gap therebetween and extending from the shell 105

10 at its lower end is an electrode 39 cooperating with the electrode 38 to provide a spark gap therebetween.

As will now be readily understood in view 5 of the preceding description, current flowing through the electrode 30 will jump to the electrode 25, then to the electrode 22, then to the electrode 19, and then to the electrode 16. From the electrode 16 the 10 current will then jump to the electrode 37, then to the electrode 38 and finally to the electrode 39 to ground, causing the occurrence of a spark at each of the spark gaps between the electrodes. As will be appreciated, the presence of a plurality of gaps in the path of flow of current to the main electrode 16 will tend to insure dependable firing of the plug even though one or more of the gaps between the electrodes 37, 38 15 and 39 are fouled. Furthermore, should one of these gaps become shorted a spark will still be produced at the remaining gaps. The cups 18, 20, 23 and 26 are provided at the periphery of the insulator so that simply 20 by removing the jacket 32, access may be had to the spark gaps within the cups. Accordingly, the ends of the electrodes projecting into the cups may be readily cleaned while the jacket 32 will normally serve to 25 enclose and protect the projecting ends of the cups housing the gaps. Furthermore, the jacket 32 will also serve to protect the projecting upper end of the insulator and will minimize the possibility of fracture 30 thereof. I accordingly provide a plug of highly efficient design and, as will be seen, a plug which may be readily employed in connection with internal combustion engines of substantially any conventional design.

40 Having thus described the invention, what is claimed as new is:

1. A spark plug including a shell, an insulator carried thereby, a main electrode projecting at one end of the insulator, an 45 electrode at the opposite end of the insulator, a third electrode upon the insulator forming spark gaps between the first and second mentioned electrodes at the side surface of the insulator, and a jacket fitting the insulator and housing said gaps.

50 2. A spark plug including a shell, an

insulator carried thereby and provided with spark cups at the side surface thereof, a main electrode projecting at one end of the insulator and extending into one of said cups, 55 an electrode at the opposite end of the insulator projecting into another of said cups, and a third electrode upon the insulator extending between the cups and forming spark gaps at the cups between said first and second mentioned electrodes.

3. A spark plug including a shell, an insulator carried thereby and provided with spark cups at the side surface thereof, a main electrode projecting at one end of the 60 insulator and extending into one of said cups, an electrode at the opposite end of the insulator projecting into another of said cups, a third electrode upon the insulator extending between the cups and forming 65 spark gaps at the cups between said first and second mentioned electrodes, and a jacket surrounding the insulator closing 70 said cups.

4. A spark plug including a shell, an 75 insulator carried thereby and provided with a plurality of peripheral spark cups, a main electrode projecting at one end of the insulator and extending into one of said cups, another electrode projecting at the opposite 80 end of the insulator and extending to another of said cups, a plurality of transverse electrodes upon the insulator extending between the cups and forming spark gaps between 85 each other as well as between said first and second mentioned electrodes, and a jacket fitting the insulator and closing said cups.

5. A spark plug including a shell, an insulator carried thereby and provided at 90 a point between its ends with a surface spark cup, and coacting electrodes upon the insulator forming a spark gap at said cup.

6. A spark plug including a shell, an insulator carried thereby and provided at a 95 point between its ends with a surface spark cup, coacting electrodes upon the insulator forming a spark gap at said cup, and a jacket surrounding the insulator housing said gap.

In testimony whereof I affix my signature.

JOHN P. RITCHHEY. [L.S.]
